DESIGN FOR A GAME APPARATUS

Allen T. Joze, Chicago, Ill., assignor to Western Equipment & Supply Company, Chicago, Ill., a corporation of Illinois

Application July 12, 1935, Serial No. 57,608

Term of patent 3½ years

To all whom it may concern:

Be it known that I, Allen T. Joze, a subject of the King of Sweden, residing at Chicago, in the county of Cook and State of Illinois, have invented a new, original, and ornamental Design for Game Apparatus, of which the following is a specification, reference being had to the accompanying drawing, forming part thereof.

The figure is a perspective view of a game apparatus embodying my design.

The right side of the design is the same as the side shown at the left in the drawing.

I claim:

The ornamental design for a game apparatus
as shown and described.

In witness whereof, I hereunto subscribe my name, this 9th day of July, 1935.

ALLEN T. JOZE.
